Inventor:

Edward H. Boucher

By

Mr. M. A. Coulter

Atty.

UNITED STATES PATENT OFFICE.

EDWARD H. BOUCHER, OF STILLWATER, NEW YORK.

FOUNTAIN SPRAY BRUSH.

Application filed June 23, 1926. Serial No. 118,004.

This invention relates to a fountain spray brush adapted for use for shampooing purposes and as a bath brush or hair brush.

The invention may be embodied in different forms, only certain ones of which are hereinafter described.

The object of the invention is to provide a spray brush provided with novel means for holding the bristles or rubber or other teeth which may be employed according to the use to which the brush is to be put.

To that end, I provide a thimble into which the bristles or the tooth may be inserted and secured to provide a unitary mounting, and the brush head has an apertured seat therethrough which is shaped to receive the thimble, retain it, and permit the water to flow therearound to have access to the bristles or the tooth held by the thimble. There are as many of the thimbles, bunches of bristles, or teeth as may be necessary to meet the requirements demanded of the particular brush which is provided with my improvement. Furthermore, the brush may have bristles alone, or only teeth, or it may be provided with both teeth and bristles.

Another object of the invention is to provide, in combination with the removable thimbles, a perforated plate which will hold all of them in their apertured seats without, however, interfering with the flow of the water to and through the seats, and to secure the holding plate in position, with capacity for detachment, by an improved arrangement of screws and nuts.

Additional objects are the provision of self-contained, unitary thimbles and bristles or teeth which may be interchangeably used, or removed, for replacement, without disturbing the remaining units comprising thimbles and bristles or teeth; also to provide an improved tube or hose connector enabling substitution of one form of brush for another by a simple manipulation; and an improved hand-hold which enables the operator to securely and yet easily grasp and retain the brush when using it as a shampoo device.

Other objects of the invention will appear from the following description. Certain embodiments of my improvements are shown in the accompanying drawings in which:

Figure 1 is a side elevation of the shampoo or bath brush;

Figure 2 is a section thereof;

Figure 3 is a plan view of the retaining plate;

Figure 4 is a detail view of a thimble and bristles held thereby;

Figure 5 is a similar view showing one form of tooth;

Figure 6 is a detail view of a thimble and another form of tooth;

Figure 7 is a longitudinal section through the hair brush, and Figure 8 is a fragmentary detail plan view, partly in section, showing the thimbles in their seats.

In Figs. 1 to 6 inclusive, the invention is shown as embodied in a shampoo and bath brush, whereas in Fig. 7 the improvements are shown in connection with a handled hair brush which is adapted for use as a spray brush or independently as a hair brush.

Referring first to Figs. 1 to 6 inclusive, the water container appears at 1, being preferably of semi-spherical form, or substantially so, or of a dome shape. The lower edge of the water container is seated in a groove 2 in the brush head 3, there being a gasket 4 to provide a tight joint. The nipple or connector 5 is provided on the water container 1 and has a flange 6 for engagement by a coupling 7 of spring wire which is carried by a clamping member 8 pivoted at 9 to the connector 10 of the hose or tube 11. The means thus provided enables the spray brush to be quickly and easily attached to the water tube or hose or disconnected therefrom to permit attachment of another spray brush whenever desired.

The water container 1 is provided with a projection 12 at its top, to which is connected a finger piece 13, a screw 14 being provided for this purpose. The finger piece 13 and the projection 12 together constitute a holding device which may be straddled by the fingers of the hand of the operator when holding the water container 1 during manipulation of the brush, slippage being prevented and yet it is unnecessary to tightly grasp the water container.

The projection 12 may be provided with a screw threaded socket 15 to receive the screw threaded end of the screw 16 which connects the brush head 3 and the water container 1. The water container is provided with a cross piece 17 through which the screw 16 passes. The head 3 is provided with a boss 18 through which the screw 16 passes. Above the head 3 is located the per-

forated plate 19 which is secured by screws 20 to brush-head 3 and lies above the thimble, now to be described, which hold the bristles or teeth.

The head 3 has apertured seats 21 which extend therethrough and are tapered from top to bottom, the smaller ends being lowermost. These seats have grooves 22, preferably two or more in number.

My invention comprehends the use of either bristles or teeth or both being used on the same brush. In each instance a thimble 23 is provided in which the bristles 24 or the tooth 25 are secured in any suitable manner. The bristles may be of any quality and stiffness desired. The teeth may be of hard or soft rubber or of composition and they may assume the form shown either in Fig. 5 or in Fig. 6, the former being a soft rubber tooth 25 and the latter a hard rubber or composition tooth 26 having a pronged lower end 27.

The thimble 23 is tapered and provided with tapered lugs or ridges 28 which are adapted to fit the seats 22 but the proportions of the parts are such that there is a space around the thimble between it and the seat 21 through which the water or fluid being used may pass to the lower face of the head 3 to have access to the bristles or the tooth. The shape of the seats and of the thimbles causes an equalization of the flow of the water and insures that it circulate around the thimbles. Furthermore, the water strikes the upper parts of the thimbles and the force of the flow is thus broken before the water reaches the bristles or teeth; consequently, it is impossible to force the water too strongly against the scalp or body when using the brush.

The plate 19 bears against the heads of the thimbles and holds all of them in position in their seats but it does not interfere with the admission of the water beneath said plate nor its access to the thimbles and seats as previously described.

It will be seen that on removing the plate 19 any thimble with its bristles or tooth may be removed and this provides for interchangeability as between thimbles and teeth and for replacement at any time. As previously set forth, the brush may be discon-

nected from the hose 11 and used independently of a water supply.

In Fig. 7 I have shown the invention embodied in hand brush form, the body or water container appearing at 29 and the handle at 30, the latter having a shouder or flange 6 similar to the one previously described, provision thus being made for attachment of the connector 10 and hose 11. By releasing the coupling 7, this form of the invention may be used separately as a hair brush. The construction is in all respects similar to that previously described except that there are two screws 16 and the plate 19 has nuts 31 located thereabove which are screwed onto the upper parts of the bosses 18.

The brush head 3 may be provided with projecting tubes or hollow bosses 32 surrounding the point of entry of the bristles or teeth in the seats 21, if desired.

What I claim is:

1. In a fountain spray brush, the combination with a brush head having seats provided with means for the passage of fluid from one side to the other side thereof, of removable fluid applying units having thimbles received in said seats, and a perforated plate bearing on said thimbles and holding them in position.

2. In a fountain spray brush, the combination with a brush head having apertured seats provided with channels in their walls, of removable fluid applying units having thimbles smaller in diameter than said seats and provided with lugs, said thimbles being received in the seats in spaced relation thereto and the lugs in the channels.

3. In a fountain spray brush, the combination with a brush head having tapered apertured seats provided with tapered channels in their walls, of removable fluid applying units having tapered thimbles smaller in diameter than said seats and provided with tapered lugs, said thimbles being received in the seats in spaced relation thereto and the lugs in the channels, and a perforated plate bearing on said thimbles and holding them in position.

In testimony whereof I affix my signature.

EDWARD H. BOUCHER.
